DESIGN FOR AN EAR CLIP OR SIMILAR ARTICLE

Sigmund Dawer, New York, N. Y.

Application July 16, 1946, Serial No. 131,610

Term of patent 3½ years

(Cl. D45—9)

To all whom it may concern:

Be it known that I, Sigmund Dawer, a citizen of the United States of America, residing in New York city, county of New York, and State of New York, have invented a new, original, and ornamental Design for an Ear Clip or Similar Article, of which the following is a specification, reference being had to the accompanying drawing, forming part thereof, wherein,

I claim:

The ornamental design for an ear clip or similar article, substantially as shown.

SIGMUND DAWER.
